ELEVATOR DOOR INTERLOCK

William Healey, Philadelphia, Pa.

Application December 13, 1950, Serial No. 200,641

3 Claims. (Cl. 187—56)

1

The present invention relates to elevator doors and is concerned primarily with an interlock that is provided between the door of the elevator itself and any of the doors leading into the elevator shaft.

At the present time it is common practice in the larger and more expensive buildings to provide some sort of power device for opening the doors leading into the elevator shaft. However, there are many smaller less expensive buildings which include elevators and in which it is not practical to provide the power devices. Thus, both the elevator door itself is manually operable and the door at each floor leading into the elevator shaft is also manually operable. Such an arrangement is extensively used where the elevators are self-operated, that is, the passenger of the elevator performs the duties of the operator.

It is evident that with the arrangement above outlined, it is necessary for a passenger in a car to perform two distinct operations, either in entering or leaving the car. As he leaves the elevator he must first open the elevator door and then the door between the shaft and the particular floor where the elevator is located and the reverse of this operation occurs when a passenger enters the elevator.

With the foregoing conditions in mind the present invention has in view as its foremost objective the provision of a mechanical interlock between the door of an elevator and any of the doors leading into the elevator shaft. With such an interlock the opening or closing movement of one door is accompanied by a corresponding movement of the door that is interlocked therewith.

The mechanical interlock of this invention is particularly adapted for use with doors of the sliding type. Thus, both the elevator door itself and the doors to the shaft should be sliding doors.

More in detail, the invention has as an object the provision of an elevator door having a projection extending outwardly from the outer face thereof. Each of the doors leading into the elevator shaft is formed with a vertically arranged socket that is open at both ends providing what is in effect a track through which said projection is adapted to pass. Thus, as the elevator moves upwardly or downwardly the projection on the elevator door will pass through the track formed by the sockets on all of the shaft doors when the latter are in closed position. However, when the elevator stops at any floor the projection of the door is received in the socket to establish the mechanical interlock between the door of the elevator and the shaft door.

2

Various other more detailed objects and advantages of the invention such as arise in connection with carrying out the above noted ideas in a practical embodiment will, in part become apparent, and in part be hereinafter stated as the description of the invention proceeds.

The invention, therefore, comprises a mechanical interlock between an elevator door and any of the several doors of an elevator shaft in which the doors are of a sliding type and which interlock permits of movement of the elevator past the shaft doors in closed position.

For a full and more complete understanding of the invention, reference may be had to the following description and accompanying drawing wherein:

Figure 1 is a fragmentary view partially in elevation and partially in section of that portion of a building in which an elevator shaft is formed; 20 Figure 2 is a detailed horizontal section taken about on the plane represented by the line 2—2 of Figure 1.

Referring now to the drawing wherein like reference characters denote corresponding parts, a building in which an elevator is installed is referred to in its entirety by the reference character B. The building B may of course have any number of floors greater than one. For the purposes of this invention it is shown as having two floors F1 and F2. The elevator shaft extends between these floors in a vertical direction. Slidably mounted on each of the floors F1 and F2 is a sliding door 10 which leads from the particular floor into the elevator shaft. The particular structure which slidably mounts the doors 10 is not illustrated because it is not a part of the present invention. Sliding mountings of this type are well known and are extensively used.

Each of the doors 10 has an outer face 11 and an inner face 12. Mounted on the inner face 12 of each door are a pair of channel plates 13 and 14 which are supported by base plates 15 and 16. The plate 13 may be secured to the plate 15 and the plate 14 to the plate 16 in any preferred manner such as by welding and the base plates 15 and 16 are secured to the door 10 in any preferred manner such as by the screw bolts represented at 17.

The plates 13 and 14 complement one another and together define a socket which is open at its upper and lower ends and which socket is in effect a track. The upper and lower edges of each of the plates 13 and 14 are bevelled as indicated at 18 to provide what are in effect flared ends for the track defined by the plates.

The door of an elevator is represented at 19

in Figure 2. This door has an inner face 20 and an outer face 21. Mounted on the outer face 21 of the door 19 is a projection which preferably takes the form of a roller 22 which is dimensioned so as to be snugly received in the tracks defined by the plates 13 and 14 on the respective doors and yet which may readily pass through these tracks which align when the doors are closed as the elevator moves upwardly and downwardly. The roller 22 is mounted on a bolt 23, the head 24 of which engages the inner face 20 of the door 19. A spacing collar 25 is interposed between the roller 22 and the outer face 21 of the door 19. A nut 26 is threaded on the free end of the bolt and holds the roller 22 in position thereon.

While the operation of the interlock above described is believed to be obvious from the description of the parts given, it may be briefly outlined by first noting that if the several doors 10 on the respective floors of the building are in closed position, the tracks or passages defined by the plates 13 and 14 are in vertical alignment. Thus, as the elevator which carries the door 19 moves upwardly and downwardly the roller 22 will pass through these aligned tracks.

When the elevator stops at any floor the roller 22 is positioned and the socket defined by the plates 13 and 14 on the door at that floor, thereby establishing a mechanical interlock between the elevator door 19 and one of the doors 10. The opening or closing of either door by a person either inside or outside of the elevator will be accompanied by a corresponding movement of the other door.

While a preferred specific embodiment of the invention is hereinbefore set forth, it is to be clearly understood that the invention is not to be limited to the exact constructions, mechanisms, and devices illustrated and described because various modifications of these details may be provided in putting the invention into practice within the purview of the appended claims.

What is claimed is:

1. In combination, a plurality of sliding elevator shaft doors in vertical alignment, a sliding elevator door, each of said elevator shaft doors being formed with a vertically arranged socket

that is open at its upper and lower ends with the several sockets on the several doors in vertical alignment, and a projection on the outer face of said elevator door adapted to pass through said sockets and assume a position in any one of them to establish a mechanical interlock between said elevator door and the shaft door having the socket in which the projection is received.

2. In combination, a plurality of sliding elevator doors in vertical alignment each having outer and inner faces, a pair of complementary plates mounted on the inner face of each of said shaft doors with said plates defining a vertical track that is open at both ends, the tracks on said several doors being in alignment and with each track also constituting in effect a socket, an elevator door having outer and inner faces, and a projection on the outer face of said elevator door adapted to pass through said tracks and be operatively positioned in any of said sockets to establish a mechanical interlock.

3. In combination, a plurality of sliding elevator shaft doors in vertical alignment each having outer and inner faces, a pair of complementary plates mounted on the inner face of each of said shaft doors with said plates defining a vertical track that is open at both ends, the tracks on said several doors being in alignment and with each track also constituting in effect a socket, an elevator door having outer and inner faces, and a roller carried by said elevator door in spaced relation to the outer face thereof with said roller having a diametrical dimension substantially corresponding to the cross dimension of said track and with said roller positioned to pass through said aligned tracks and come to rest in any of the sockets defined thereby to establish a mechanical interlock.

WILLIAM HEALEY.
